R. A. MYERS

WAITER'S PUNCH

Filed Nov. 12, 1923

Inventor

ROY A. MYERS

C. D. Enochs

By

Attorney

UNITED STATES PATENT OFFICE.

ROY A. MYERS, OF ST. PAUL, MINNESOTA.

WAITER'S PUNCH.

Application filed November 12, 1923. Serial No. 674,324.

To all whom it may concern:

Be it known that I, Roy A. Myers, a citizen of the United States, and a resident of St. Paul, in the county of Ramsey and State of Minnesota, have invented certain new and useful Improvements in Waiters' Punches, of which the following is a specification.

One object of my invention is to provide a punch having a container as a part thereof for receiving a roll of printed checks.

Another object is to provide means for straightening the checks as they are fed from the roll.

Another object is to provide improved means for punching or notching various points of the check as it is fed from the roll.

Another object is to provide means for preventing the roll of checks from getting out of proper position.

Another object is to provide an improved form of cap or cover for the container.

Another object is to provide an improved form of waiter's check.

With these and incidental objects in view, the invention consists of certain novel features of construction and combination of parts, the essential elements of which are hereinafter described with reference to the drawing which accompanies and forms a part of this specification.

In the drawing, Figure 1 is a section taken on the line 1—1, Figure 2; Figure 2 is a top view of the punch as shown in Figure 3; Figure 3 is a section taken on the line 3—3, Figure 1; Figure 4 is a section taken on the line 4—4, Figure 1; and Figure 5 is a plan view of one of the checks printed on the roll of paper and carried in the container.

As shown in Figures 1 and 3, the container 1 has a stud 2 centrally mounted therein, whose free end is formed into a ball shape 3. The cover or lid 4 has a pair 45 of spring catches 5 centrally mounted and adapted to receive the ball 3 of the stud 2 and hold the cover in close engagement with the container.

A strip of metal 6, riveted to the container, has a slot 7 therein registering with a similar slot in the container through which the ribbon of paper 8 from the roll 9 may be brought out of the container. This paper

is fed through the creasing device 10, better shown in Figure 4, which serves to crease the paper as it comes from the roll, thereby straightening out the curl that would otherwise remain in the ribbon when it is torn off to form a check.

From the creaser the ribbon of paper passes under the punch, or notcher, 11 and from there under the guide 12, the top of which serves as a cutting edge against which a check may be torn off at the desired point. Sufficient space is left at 13 so the ribbon may be fed with the thumb through the guide 12 to a sufficient extent to allow it to be grasped at the farther end of the guide so the check may be pulled out to any point desired.

In the form of check shown in Figure 5 I have provided a place at 14 where the name of the restaurant may be printed in, a space 15 which is to indicate the number of persons for whom the check is issued, a place at 16 in which may be indicated the amount in dollars for which the check is

being issued, and a portion at 17 in which may be indicated the amount in cents or fractions of dollars for which the check also reads, and the portion 18 is left for advertising matter. Along the left-hand side of the check, as it is shown in the drawing, are printed spaces in which the check is to be notched by the punch 11. These are preferably red and black, as indicated, and one series of columns is reserved for the odd numerals and the other series of columns for the even numerals for the portions indicating persons, dollars, and cents, so that by notching the proper point along the left-hand side of the check the check is thus made to indicate the number of persons and the amount of the charge, both in dollars and cents, and by having the notches all on one side of the check the operation of notching the checks is greatly facilitated, while at the same time there is plenty of room for making the indicating notches, as the numerals representing the persons, dollars and cents are spaced but a line for each numeral runs to the corresponding point that is to be notched.

In using the device, the operator will pull the check from the roll, and if there are two people for whom the check is be-

ing issued, and their charge is \$2.75, the waiter will pull the check out until the numeral 2 in the "Persons served" portion of the check is opposite the punch and will then notch the indicia under the punch; she will then pull the check further until the numeral 2 in the "Dollars charged" portion of the check is opposite the punch and will then notch the indicia under the punch; she will then pull the check further until the numeral 75 in the "Cents charged" portion of the check is opposite the punch and will punch the indicia under the punch; she will then pull the check to the end and tear it off along the line 19 against the cutting edge of the guide which is provided for that purpose; and with her thumb on the ribbon at 13 she will feed the ribbon out beyond the guide ready to be pulled out when she wishes to make out the next check.

The advantages of the check and punch are many in that it is neat, simple of construction, compact, is carried by hook or chain attached to the ring provided for that purpose, and carries an extraordinarily large number of checks on account of the checks being put up in a roll. Also, it has the great advantage of marking all of the points of the check on the same side of the check so it is practically impossible for the cashier to overlook any of the points marked.

While I have described my invention and illustrated it in one particular design, I do not wish it to be understood that I limit myself to this construction, as it is evident the application of the invention may be varied

in many ways within the scope of the following claims.

Claims:

1. In a check punch the combination of a container adapted to carry therein a ribbon of checks in a roll, means for leading said ribbon from said container, and straightening means for taking the roll out of the ribbon as it is lead from said container and means carried by said container for notching said checks.

2. In a check punch the combination of a container adapted to carry a roll of checks therein in the form of a continuous ribbon, means for leading said ribbon from said container, a punch carried by said container and positioned so the ribbon will pass thereunder, a guide for said ribbon positioned beyond said punch and adapted to prevent said ribbon from feeding back into said container after said ribbon has been punched.

3. In a check punch the combination of a container adapted to carry a roll of checks, means for leading said ribbon-like checks from said container, straightening means carried on said container through which said ribbon passes, a punch carried by said container under which said ribbon passes, and a guide carried by said container through which said ribbon passes, said guide and said punch being spaced apart sufficiently to allow a thumb to be inserted therebetween for the purpose of slipping the check through said guide.

ROY A. MYERS.
